Edson Bros.

UNITED STATES PATENT OFFICE.

JEFFERSON GRUBE, OF AUBURN, INDIANA.

GRAIN-SEPARATOR.

SPECIFICATION forming part of Letters Patent No. 252,314, dated January 17, 1882.

Application filed March 14, 1881. (No model.)

To all whom it may concern:

Be it known that I, JEFFERSON GRUBE, a citizen of the United States, residing at Auburn, in the county of De Kalb and State of Indiana, have invented certain new and useful Improvements in Grain-Separators; and I do hereby declare the following to be a full, clear, and exact description of the invention, such as will enable others skilled in the art to 10 which it appertains to make and use the same, reference being had to the accompanying drawings, and to the letters or figures of reference marked thereon, which form a part of this specification.

15 The invention relates to grain-separators of the class employing a fan; and the novelty consists in the construction and arrangement of parts, as will be more fully hereinafter set forth, and specifically pointed out in the claim.

20 The invention is designed as an improvement upon the device granted to me December 7, 1880, in which differentially-inclined boards served, in connection with the fan, for the useful purposes therein set forth.

25 The object of this invention is to improve upon the construction therein set forth, and to that end I employ in this device, between the sides of a rectangular frame composed of inclined side boards and proper end braces, a series of regularly-graduated different-sized

30 boards pivoted between the sides, and all connected pivotally to a longitudinal bar having a ratchet portion, which passes through a kerf in the end board located in the larger end of the frame, to which end board is secured a spring-arm, which operates in the rack portion to allow the adjustment at will of the inclines of the boards, and to thus control the feed to the shoe, and also the volume of current, as 35 40 will be obvious from the construction shown in the drawings.

The invention, in connection with the device set forth and described in the patent previously

referred to, is fully shown in the accompanying drawings, which form a part of this specification, and in which— 45

Figure 1 is a perspective view, partially in section; Fig. 2, a detail, and Fig. 3 a perspective view of one of the boards.

To enable others skilled in the art to make 50 and use my invention, I will describe the construction and mode of operation of the same, referring to the drawings, in which similar letters of reference indicate like parts in all the figures. 55

A represents the inclined side boards, B the cross-board at the smaller ends thereof, and B' the similar cross-board at the larger ends, which together constitute the frame. In this frame are pivoted, at points marked c c, 60 the boards C, which are regularly graduated in size from either end to correspond approximately with the graduation of the side pieces, A. These graduated boards are pivoted at or near their lower edges to a rack-bar, D, having a toothed portion, d, within which operates a spring-pawl, f, secured to the end board, B'. 65

It will be observed that the pitch of the boards C may be varied at will.

In case the boards are made of wood, the 70 ends are received in slots l of castings L, having pivoting lugs, as shown in Fig. 3.

What I claim as new, and desire to secure by Letters Patent of the United States, is—

As an improvement on my device as patented to me December 7, 1880, No. 235,223, the graduated partitions, in combination with means for adjusting the same, substantially as and for the purposes hereinbefore set forth. 75

In testimony whereof I affix my signature 80 in presence of two witnesses.

JEFFERSON GRUBE.

Witnesses:

GEORGE B. ADAMS,
A. S. LEAS.
